UNITED STATES PATENT OFFICE.

JULIUS KAHN, OF YOUNGSTOWN, OHIO, ASSIGNOR TO TRUSCON STEEL COMPANY, OF YOUNGSTOWN, OHIO, A CORPORATION OF MICHIGAN.

FABRICATED POLE.

Application filed April 6, 1927. Serial No. 181,466.

This invention relates to fabricated metal poles, and more particularly to a pole which tapers from its base towards its top.

One of the objects of the invention is to provide a fabricated pole whose parts are effectively arranged and secured together to obtain maximum strength and rigidity, thereby providing a pole which is strong, durable, comparatively light, and also economical to manufacture.

A further object of the invention is to provide a novel base construction which may be filled with earth or the like to provide a weight or anchor at the bottom of the pole thereby to firmly hold it in position in the ground.

With the above and other objects in view which will more readily appear as the nature of the invention is better understood, the same consists in the novel construction, combination, and arrangement of parts herein-after more fully described, illustrated and claimed.

A preferred and practical embodiment of the invention is shown in the accompanying drawings in which:—

Figure 1 is a detail view illustrating the application of the invention, the pole being broken at the center in view of its comparatively great height in proportion to its width.

Figure 2 is an enlarged detail side elevation of the base.

Figure 3 is a horizontal cross section on the line 3—3 of Figure 1.

Figure 4 is a horizontal cross section taken on the line 4—4 of Figure 1.

Figures 5 and 6 are horizontal cross sectional views respectively taken on the lines 5—5 and 6—6 of Figure 1.

Similar reference characters designate corresponding parts throughout the several figures of the drawings.

In the embodiment of the invention shown the body A of the pole consists of a plurality of angle-iron members 1 of suitable length arranged with their included angles facing each other so that the outer corners 2 thereof form the corners of the completed pole while the meeting side edges thereof at the top may be placed in contact and welded together at one or more points as indicated at 3. Thus, the top portion of the pole forms a hollow rectangle and for a portion

55 of its length is of uniform width but at the

point of the last weld 3, the angle members 1 begin to diverge uniformly and progressively toward the base of the pole designated generally as B thereby to provide a tapered pole structure. The tapering body portion 60 A formed by the spaced angle members is also provided with a plurality of transverse battens which are preferably metal strips welded to adjacent flanges of the angle members 1, and spaced closer to each other near 65 the ground level and further apart near the top of the pole.

At a point below the ground level designated by the dotted line x—x in Figure 1, the pole is formed with a special base which 70 is constructed not only with a view to economy of metal but to also provide a firm and effective anchorage for the pole in the earth. This base consists of a plurality of upper plates 5 which are bowed outwardly at their 75 medial portions and attached at their side edges to the flanges of the angle members. Four of these plates are used to provide a hollow open box portion near the top of the base, and by reason of their bowed formation the individual members resist inward bending movement due to the pressure of the earth about the bottom of the pole. In other words, the purpose of providing the 80 outwardly bowed plates 5 is to prevent them 85 from readily crushing in from the weight outside or when a load is applied to the top of the pole.

The bottom ends of the angle members 1 are connected by the plates 6—6 whose side 90 edges are welded to one flange of adjacent angle members, and are also connected by the flanged plates 7 which are not only welded to the outside of the angle members 1—1 as clearly shown in Figure 5, but are 95 also provided with the inwardly turned bottom flanges 8 which cover and protect the bottom ends of the angle members. These flanges 8 not only serve as a retainer for earth within the relatively box-like inclosure 100 provided by the base structure, but also assist in preventing penetration of the relatively sharp bottom ends of the angle members into the earth which might cause the pole to sink under its own weight if it 105 should be placed in earth which is likely to become soft or soggy under rainy or similar conditions.

The upper series of plates 5 and the lower series of plates 6 and 7 provide in effect 110

spaced bands or strips of metal of relatively great width as compared with the angle members 1, and said angle members between said series of plates, are connected at all 5 sides with the crossing brace members 9 and 10 which take the side thrusts or strains imparted to the base and assist in preventing the rupture of the welds which hold the angle members and plates 5, 6 and 7 together.

When the pole is placed in the earth and the base B is also filled with earth or the like, a strong and firm anchorage for the pole is provided.

15 Without further description it is thought that the features and advantages of the invention will be readily apparent to those skilled in the art, and it will of course be understood that changes in the form, proportion and minor details of construction 20 may be resorted to, without departing from the spirit of the invention and scope of the appended claims.

I claim:—

25 1. A fabricated metal pole including angle members forming the body of the pole, and an anchoring base construction for the bot-

tom of the pole, said base construction comprising upper and lower relatively deep plate members, said upper plate members 30 being bowed outwardly to resist inward pressure of the earth, and said lower plate members including relatively deep body portions and certain of said plate members having inwardly projecting flanges extending 35 beneath the lower ends of the angle members to resist sinking movement of the pole, and braces connecting the angle members between said plates.

2. In a fabricated metal pole, angle members forming the corners of the pole, an anchoring base including an upper and a lower series of spaced plates, each plate of the upper series being bowed outwardly at its medial portion to resist inward pressure 45 of the earth, and the oppositely disposed plates of the lower series having inturned flanges at the bottom edges to resist sinking movement of the pole, and crossing brace strips connecting the angle members between the plates.

In testimony whereof I hereunto affix my signature.

JULIUS KAHN.
